UNITED STATES PATENT OFFICE.

HENRY BRIGGS, OF PHILADELPHIA, PENNSYLVANIA.

BREECH-LOADING FIRE-ARM.

SPECIFICATION forming part of Letters Patent No. 327,860, dated October 6, 1885.

Application filed June 11, 1885. Serial No. 168,374. (No model.)

To all whom it may concern:

Be it known that I, HENRY BRIGGS, a citizen of the United States, residing in Philadelphia, Pennsylvania, have invented certain 5 Improvements in Fire-Arms, of which the following is a specification.

My invention consists of certain improvements in the construction of breech-loading fire-arms, as fully described and claimed here-10 in after.

In the accompanying drawings, Figure 1 is a longitudinal section of a fire-arm embodying 15 my invention, with the breech closed and the hammer down. Fig. 2 is a similar view with the breech-block and hammer drawn back, the breech-block being shown in outside view. Fig. 3 is a detached perspective view of the 20 sliding breech-block and a portion of its operating-lever. Fig. 4 is a transverse section on the line 1 2, Fig. 1; and Fig. 5 is a detached view of the end of the barrel with the shell-extracting devices.

A is the barrel of the fire-arm, carried by the frame B, which is attached to the usual 25 stock D.

To an opening through the frame B is adapted a vertically-sliding breech-block, E, which carries the firing-pin e, adapted to be thrown forward by the blow of the hammer 30 and returned by a suitable spring, e'. This sliding breech-block is controlled in its movements by the lever F, hinged at f to the frame, and which is shaped to form at the same time a guard for the trigger.

35 Instead of making the connection between this operating-lever and the sliding breech-block through the medium of a link, as is commonly done, I form in the lower part of the breech-block a T-headed slot, E', Fig. 3, 40 to which is adapted a T-head, F', on the lever F, the slot E' being of such a depth, Fig. 1, as to allow of the proper movement of the T-head F' in swinging on its pivot f. If desired, the T-head may be on the block and the slot in the 45 lever; but in any case the slot should be open at the edge, in order to permit of the ready detachment of the parts for cleaning or repairs.

H is the hammer, which is pivoted at h to 50 the frame, and is acted on by a spring, G,

which I prefer to form of untempered round wire, having a coil or turn with two arms, one arm, g', acting on the hammer H, and the other secured at g to the bottom of the frame B. That arm of the spring which is secured 55 to the frame is extended beyond its point of fastening g and bent up to act on the short arm of the trigger J, which is adapted to engage with the usual notches on the short arm of the hammer H.

It will be observed, on reference to Fig. 1, that the arm g' of the spring which acts upon the hammer is adapted to a slot in the end of the latter, while a stop, b, is formed on the upper part of the frame B for the arm g' of 60 the spring, the relation of this stop b to the hammer or the slot therein being such that the arm g' of the spring will stop before the hammer H reaches the end of its movement, and, consequently, while the hammer will be 65 thrown forward by the spring with sufficient force against the firing-pin to fire the cartridge the hammer will be allowed to rebound back from the firing-pin and permit the latter to return to its normal position.

I prefer to form on the lower arm of the hammer, in addition to the usual notches, a supplementary notch, h', which I term a "rebound" notch, and with which the nose of the trigger will engage when the hammer 70 rebounds, to hold the latter back from the firing-pin, as shown in Fig. 1.

In order to make the gun self-cocking I form on the hammer H, on one side thereof, a projection or pin, i, Fig. 2, and on the sliding breech-block I secure a projecting arm, I, Figs. 2 and 3, which, as the breech-block E is pulled down or descends, will engage with or 85 strike against the pin i on the hammer and draw the latter down to the cocked position 90 shown in Fig. 2. This arm I may be secured to the breech-block in any suitable manner; but I prefer to secure it by providing on the enlarged end of the arm a dovetail inserted from below into a dovetailed recess in the block 95 and secured by a screw, i', as shown in Fig. 3.

To discharge the empty shell of the cartridge, I provide a sliding extractor, K, which consists of an L-shaped plate adapted to a dovetailed groove at the rear end of the bar- 100

rel and having its short arm projecting to the edge of the bore below the rim of the cartridge. This extractor is acted on by a spring, *k*, which tends to keep it in the closed position illustrated in Figs. 1 and 2. This extractor is provided with a projection, *k'*, adapted to be acted on by a yielding nose, *l*, of the lever *L*, pivoted to the frame and having its short arm adapted to be acted on by the sliding breech-block. In the present instance the short arm of this lever *L* projects into a recess, *m*, in the sliding breech-block, the opposite ends of this recess, Fig. 1, forming projections to act on the lever to move it from the position shown in Fig. 1 to that shown in Fig. 2, and return it to its normal position, Fig. 1.

The yielding nose *l* of the lever *L* consists in the present instance of a pivoted arm, which is acted on by a spring, *l'*, Fig. 5, tending to throw the arm outward to keep it in engagement with the projection *k'* on the sliding extractor.

On a cross-piece of the frame is formed a beveled projection, *p*, Figs. 1 and 2, for a purpose which I will now explain.

When the parts are in the closed position shown in Fig. 1, the yielding nose *l* of the lever *L* engages with the projection *k'*, so that when the breech-block is pulled down and the upper end of the slot *m* engages with the short arm of the lever *L* the yielding nose *l* will push the sliding extractor *K* outward, as illustrated in Fig. 5, to eject the empty shell from the fire-arm; but as soon as the nose *l* of the lever *L* comes into contact with the beveled projection *p* the said nose will be thrown out of engagement with the projection of the extractor *K*, and the latter, under the action of the spring *k*, will immediately return to its closed position.

I claim as my invention—

1. The combination of the frame of a fire-arm and the sliding breech-block adapted thereto with an operating-lever connected to

the breech-block and pivoted to the frame, the 45 said lever or block having a T-headed slot open at the end, and the other having a T-head adapted to the slot, substantially as set forth.

2. The combination of the frame of a fire-arm 50 and the hammer having a slot at its rear with a spring secured to the frame, and having one end, *g'*, adapted to the slot in the hammer, and a stop on the frame to limit the movement of the spring, substantially as set 55 forth.

3. The combination of the barrel of a fire-arm 60 and an extractor carried by the barrel with a sliding breech-block, a lever to impart an outward movement to the extractor and acted on by the sliding breech-block, devices, substantially as described, to disengage the lever from the extractor at the end of its outward movement, and a spring to return the extractor to its closed position. 65

4. The combination of the barrel of a fire-arm 70 having an extractor, *K*, and a return-spring therefor, with a lever, *L*, pivoted to the frame and having a yielding nose to act on the extractor, but adapted to be released therefrom at the end of its outward movement, substantially as set forth. 70

5. The combination of the barrel of a fire-arm 75 having an extractor, *K*, and a return-spring therefor, with a lever, *L*, pivoted to the frame and having a yielding nose to act on the extractor, and a beveled projection, *p*, to release the yielding nose from the extractor at the end of the outward movement of the latter, substantially as and for the purpose set forth. 80

In testimony whereof I have signed my name to this specification in the presence of two subscribing witnesses.

HENRY BRIGGS.
